NOVELTY ORNAMENT

Laurie J. Campbell, Erie, Pa., assignor to Louis Marx & Company, Inc., New York, N. Y., a corporation of New York

Application June 11, 1946, Serial No. 676,013

12 Claims. (Cl. 63—20)

1

This invention relates to novelties, and more particularly to ornaments such as a jewelry pin or brooch.

One object of the present invention is to provide an ornament of novel and amusing character. A more particular object is to provide an ornament simulating a traffic signal, and provided in front with readily accessible means to select one of the signal indications. The ornament may have differently colored inserts corresponding to traffic lights.

A further object of the invention is to provide such an ornament which may be made inexpensively, and which will not depend on reflection requiring bright or direct illumination. The operation of the ornament does not depend on the use of real or artificial gems, and instead the colored inserts may be made of an opaque or a translucent plastic. Enamel too may be used.

In accordance with still another feature and object of the invention, the traffic light simulation is preferably mounted on a back-plate or shield, which supports it and steadies it in proper position, and sets it off to advantage.

To accomplish the foregoing objects, and such other objects as will hereinafter appear, my invention resides in the ornament elements and their relation one to another, as are hereinafter more particularly described in the following specification. The specification is accompanied by a drawing, in which:

Fig. 1 is a front elevation of a ladies' jewelry pin or brooch, embodying features of the invention;

Fig. 2 is a horizontal section taken approximately in the plane of the line 2—2 of Fig. 1;

Fig. 3 is a front elevation of a modified form of the invention;

Fig. 4 is a vertical section taken approximately in the plane of the line 4—4 of Fig. 3;

Fig. 5 is a horizontal section taken approximately in the plane of the line 5—5 of Fig. 3;

Fig. 6 is a transverse section drawn to enlarged scale through one edge of the signal per se, and is taken approximately in the plane of the line 6—6 of Fig. 7; and

Fig. 7 is an enlarged side elevation of a fragmentary portion of the edge of the signal per se.

Referring to the drawing, a first form of the invention is shown in Figs. 1 and 2, and a second form of the invention is shown in the remaining figures. In both forms, there is a simulated traffic signal T with indications corresponding to "Stop," "Caution" and "Go," and an element E movably mounted on the front of the orna-

2

ment to select one of the indications. The simulated traffic signal T is preferably mounted on a suitable back-plate or shield S.

Considering the first form of the invention in greater detail, the traffic signal T may be pressed out of sheet metal, and has red, amber and green inserts 12, 14 and 16, respectively. These may be made of a suitable molded plastic, and may, if desired, be opaque, although translucent materials also look well. The inserts are secured in place by suitable frames or bezels 18, usually made of metal.

In the present case the shield S is simply a circle of sheet metal 20, but it will be understood that other ornamental outlines may be employed. The shield is shown flat, but may be dished at the back and convexed at the front, so that its peripheral edge will lie closely against a garment to which it is pinned. On its back the shield has 20 a pin 22 (Fig. 2), pivoted at 24, and received in a rotating lock or clasp 26 which may be of conventional construction. The traffic light signal T is secured to the shield S in any desired manner, and in the present case is shown provided with 25 rearwardly bent tongues 28 received through slots in the shield.

In the present relatively simple species of the invention, the element E is an arrow or other suitable pointer. One end 30 is frictionally 30 pivoted to the shield 20 at 32, while the other end 34 is manually movable over the front of the pin to point to any selected one of the signals. The pointer may be made of metal or other opaque material, and is readily accessible 35 at the front of the ornament. It moves not only on top of the shield, but preferably on top of at least the edge portion of the traffic light simulation. The pointer is shown in solid lines in its mid-position, which usually corresponds to 40 the amber or yellow signal. The dotted-line positions show the pointer directed toward either the red or the green signal.

Referring now to the second form of the invention, shown in Figs. 3 and 7, the element E 45 is a shutter slidably movable over the traffic light simulations. With only two simulated lights (red and green), a single shutter is adequate, it covering one of the light simulations, and exposing the other. With three signals as here 50 shown, there are two shutters 40 and 42. These cover any two of the simulated lights, and expose only the third. In Figs. 3 and 4, it is the middle or amber signal that is exposed, while the red and green signals are covered.

55 Considering the arrangement in greater detail,

the simulation of the traffic signal may be formed of a single piece of sheet metal, it being channeled at the middle or raised at the edges, to provide guides or ways 44. The colored inserts are disposed in the channel between the ways 44, as is best shown in Figs. 5 and 6. The base portion 46 is secured to the back-plate or shield 48.

The shutter elements 40 and 42, preferably of sheet metal, have side edges which are rearwardly and reversely folded, as indicated at 50 in Fig. 6. These provide a sliding fit on the guides 44. Triangular tabs of metal are struck outwardly as shown at 52 in Figs. 6 and 7. (In these figures the shield has been omitted to simplify the drawing). These tabs simulate the visors of traffic lights facing the "cross-street," and are provided here not only for improved appearance (their sole purpose in Fig. 1), but to provide means readily grasped by the fingers for sliding the shutters to one position or another. The vertical motion of the shutters is limited by the end portions 54 and 56 of the simulated traffic signal, these being struck outwardly, as is best shown in Fig. 4.

As before, there is a relatively large back shield 48, which is provided with a pin 60 pivoted at 62, and having its pointed end received in a safety clasp or lock 64.

It is believed that the improved novelty or ornament of my invention, as well as the advantages thereof, will be apparent from the foregoing detailed description. The ornament is preferably in the form of a ladies' pin or brooch, but might be made as a clip or otherwise secured to a ladies' garment. The indicator means is located at the front of the ornament, where it is conspicuous, and readily accessible for movement to any one of the signal indications. The large-area shield supports and steadies the traffic light portion in proper position. The ornament may be made inexpensively. The operation does not depend on reflection from the back, and the colored inserts therefore need not be made of real or simulated jewels.

It will be understood that while I have shown an ornament with three simulated traffic signals (for example, red, amber and green), it may also be made with two (for example, red and green). It will also be understood that yellow and amber are here used interchangeably, and that other colors may be used if appropriate. The shield or backplate may be given any desired ornamental outline.

It will be understood that while I have shown and described the invention in several preferred forms, changes may be made in the structures disclosed, without departing from the spirit of the invention as sought to be defined in the following claims.

I claim:

1. An ornament comprising a simulation of a traffic light signal, said simulation including red and green colored inserts corresponding to red and green signal lights, and an element movably mounted over the front of said ornament to select one of the colored light simulations.

2. A jewelry pin or brooch comprising a simulation of a traffic light signal, said simulation including red, yellow and green colored inserts corresponding to red, yellow and green signal lights, and an opaque element movably mounted over the front of said pin or brooch to select one of the colored light simulations.

3. An ornament comprising a shield, a simula-

tion of a traffic light signal on said shield, said simulation including red and green colored inserts corresponding to red and green signal lights, and an element movably mounted over the front of said ornament to select one of the colored light simulations.

4. A jewelry pin or brooch comprising a shield, a simulation of a traffic light signal on said shield, said simulation including red, yellow and green colored inserts corresponding to red, yellow and green signal lights, and an opaque element movably mounted over the front of said pin or brooch to select one of the colored light simulations.

5. An ornament comprising a shield, a simulation of a traffic light signal on said shield, said simulation including red and green colored inserts corresponding to red and green signal lights, and an opaque element movably mounted in front of said ornament, said element being in the form of a frictionally pivoted pointer which may be moved to point to a selected one of the colored light simulations.

6. A jewelry pin or brooch comprising a shield, a simulation of a traffic light signal on said shield, said simulation including red, yellow and green colored inserts corresponding to red, yellow and green signal lights, and an opaque element movably mounted in front of said pin or brooch, said element being in the form of a frictionally pivoted arrow which may be moved to point to a selected one of the colored light simulations.

7. An ornament comprising a simulation of a traffic light signal, said simulation including red and green colored inserts corresponding to red and green signal lights, and an element movably mounted in front of said ornament, said element being in the form of a frictionally pivoted pointer which may be moved to point to a selected one of the colored light simulations.

8. A jewelry pin or brooch comprising a simulation of a traffic light signal, said simulation including red, yellow and green colored inserts corresponding to red, yellow and green signal lights, and an opaque element movably mounted in front of said pin or brooch, said element being in the form of a frictionally pivoted arrow which may be moved to point to a selected one of the colored light simulations.

9. An ornament comprising a simulation of a traffic light signal, said simulation including red and green colored inserts corresponding to red and green signal lights, the side edges of said simulation providing guides or ways, and a shutter element slidably mounted on the aforesaid guides or ways in front of said ornament, said shutter being slidable to positions which conceal or cover a light simulation and expose a selected light simulation.

10. A jewelry pin or brooch comprising a simulation of a traffic light signal, said simulation including red, yellow and green colored inserts corresponding to red, yellow and green signal lights, the side edges of said simulation providing guides or ways, and two shutter elements slidably mounted on the aforesaid guides or ways in front of said pin or brooch, said shutter elements being slidable to positions which conceal or cover two of the light simulations and expose only a selected light simulation.

11. An ornament comprising a shield, a simulation of a traffic light signal on said shield, said simulation including red and green colored inserts corresponding to red and green signal lights, the side edges of said simulation being raised or

spaced away from the shield to provide guides or ways, and a shutter element slidably mounted on the aforesaid guides or ways in front of said ornament, said shutter being slidable to positions which conceal or cover a light simulation and expose a selected light simulation.

12. A jewelry pin or brooch comprising a shield, a simulation of a traffic light signal on said shield, said simulation including red, yellow and green colored inserts corresponding to red, yellow and green signal lights, the side edges of said simulation being raised or spaced away from the shield to provide guides or ways, and two opaque shutter elements slidably mounted on the aforesaid

guides or ways in front of said pin or brooch, said shutter elements being slidable to positions which conceal or cover two of the light simulations and expose only a selected light simulation.
